No. 701,200.

Patented May 27, 1902.

H. J. HENGEVELD & A. E. ADAMS.

TIRE HEATER.

(Application filed Apr. 26, 1901.)

(No Model.)

UNITED STATES PATENT OFFICE.

HENRY J. HENGEVELD AND ALBERT E. ADAMS, OF HIGH SPRINGS, FLORIDA.

TIRE-HEATER.

SPECIFICATION forming part of Letters Patent No. 701,200, dated May 27, 1902.

Application filed April 25, 1901. Serial No. 57,449. (No model.)

To all whom it may concern:

Be it known that we, HENRY J. HENGEVELD and ALBERT E. ADAMS, of High Springs, in the county of Alachua and State of Florida, have 5 invented a new and useful Improvement in Tire-Heaters, of which the following is a specification.

This invention is an improvement in machines for heating tires of locomotives and 10 the like to enable the removal of such tires when worn without requiring the removal of the wheel, and has for an object to provide an improved construction of burner-ring for 15 encircling the tire whereby to secure a more rapid heating thereof; and the invention consists in certain novel constructions and combinations of parts, as will be hereinafter described and claimed.

In the drawings, Figure 1 is a side view of 20 tire-heating apparatus embodying our invention. Fig. 2 is a detail sectional view of the burner.

The ring B is designed to encircle the tire and is supported on a base K, having uprights K' provided with clasps K² for holding 25 the ring so the latter can be supported in an upright position, as shown. The ring is composed of a series of short tube-sections B', threaded at their ends in the T connections 30 B², which are provided centrally with the inwardly-projecting nozzles forming the burners b. The burners b each have a perforated plate l in rear of its outlet operating to give a 35 solid blue blaze. The inwardly-projecting nozzles are important, as by them the heating-

blaze is discharged directly against the tire and is permitted to spread out along the surface thereof, effecting a thorough heating thereof, as desired. Further, by making the rings in sections and connecting the sections 40 by the nozzle connections if any of the latter or the sections become injured or worn it can be readily replaced, and sections can be added or removed to conveniently increase or decrease the size of the ring to adapt it to operate on different sizes of wheels. The gas or hydrocarbon fuel may be supplied to the ring through the tube J from any desired source.

Having thus described our invention, what we claim as new, and desire to secure by Letters Patent, is—

1. In a tire-heater, a ring composed of tube-sections, T connections between said sections and threaded thereto, inwardly-projecting nozzles or burners on said connections, and the stand having clasps holding said ring whereby it may be supported in an upright position substantially as set forth.

2. A tire-heating ring composed of a series of tubular sections, a series of nozzles, and means for connecting the tubular sections and nozzles whereby sections and nozzles may be added or removed to vary the size of the ring substantially as set forth.

HENRY J. HENGEVELD.
ALBERT E. ADAMS.
